T. P. BROOKE,
SAFETY BALLOONETTE FOR BOATS AND THE LIKE,
APPLICATION FILED FEB. 2, 1917.

1,240,414.

Patented Sept. 18, 1917.

INVENTOR.
Thomas P. Brooke.

BY ATTORNEY

UNITED STATES PATENT OFFICE.

THOMAS P. BROOKE, OF CHICAGO, ILLINOIS, ASSIGNOR TO THE BROOKE AIRCRAFT COMPANY, A CORPORATION OF DELAWARE.

SAFETY-BALLOONETTE FOR BOATS AND THE LIKE.

1,240,414.

Specification of Letters Patent. Patented Sept. 18, 1917.

Application filed February 2, 1917. Serial No. 146,251.

To all whom it may concern:

Be it known that I, THOMAS P. BROOKE, a citizen of the United States, residing at Chicago, in the county of Cook and State 5 of Illinois, have invented certain new and useful Improvements in Safety-Balloonettes for Boats and the like, of which the following is a specification.

This invention relates to improvements in 10 boats, but more particularly to safety devices therefor, and one of the objects of the invention is to provide an improved balloonette adapted to be incorporated or arranged within the boat body to be protected 15 thereby, and which will, should the body of the boat become crushed or injured, serve to buoy up the boat and prevent the same from sinking.

A further object is to provide an improved device of this character by means 20 of the use of which the necessity of building or constructing air and liquid tight compartments within the boat body for the purpose of preventing the same from sinking 25 will be obviated, and the compartments for the reception of the balloonettes may be constructed of comparatively light walls.

A further object is to provide an improved device of this character which may 30 be inflated when desired to cause it to fill the compartment, and which may be readily removed from the compartment when deflated for inspection purposes and also for inspection of the compartment.

To the attainment of these ends and the accomplishment of other new and useful objects as will appear, the invention consists in the features of novelty in substantially the construction, combination and arrangement of the several parts hereinafter 40 more fully described and claimed and shown in the accompanying drawing illustrating the invention and in which—

Figure 1 is a view of a boat body, partly 45 in side elevation and partly in section, constructed in accordance with the principles of this invention.

Fig. 2 is a top plan view thereof.

Fig. 3 is an enlarged detail sectional 50 view of one of the compartments showing a balloonette in position therein.

Fig. 4 is a detail perspective view of one of the balloonettes.

Fig. 5 is a sectional view taken on line 55 5—5, Fig. 2.

Referring more particularly to the drawing, the numeral 10 designates generally a boat body having a compartment 11 in the bow thereof and compartments 12 in the rear portion thereof.

The compartments 11 and 12 are formed in any desired or suitable manner, with the walls of the boat body, preferably by means of light partitions 13 which may be of lattice work construction or of any desired or suitable construction which will hold the adjacent balloonettes separated from each other.

Arranged within each of the compartments is a sack 14 constructed of any suitable flexible water and air proof material, and the sack conforms in shape to the shape of the compartment in which it is to be arranged, and is of a size that when inflated will substantially fill the compartment. 70 The sack is provided with an inflation valve 15 by means of which it may be inflated, and if desired, although it is not necessary, a casing 16 may be provided for the sack. This casing may be of any desired 75 size with respect to the sack, but is preferably of a size slightly smaller than the size of the sack when the latter is inflated so that the walls of the sack will be relieved of the pressure of the air within the sack 80 and which pressure will be exerted upon the walls of the casing 16.

Each of the compartments is provided with an opening 17 through which the sack may be inserted into and removed from the compartment and through which opening access may be readily had to the inflation valve 15. After the sack has been inflated, the inflation valve 15 may be forced within the compartment as shown in Fig. 3 and a closure 85 18 will close the opening 17.

With this improved construction it will be manifest that should the boat become crushed or broken, the balloonettes will prevent the same from sinking and as the sacks 100 are constructed of flexible material, they will yield when exterior pressure is exerted thereon and the sacks will be prevented from becoming punctured. Furthermore, very light partitions may be employed to separate the sacks and this not only reduces the cost of manufacture but also results in a light, strong but durable structure.

While the preferred form of the invention is herein shown and described it is to be 110

understood that many changes may be made in the details of construction and in the combination and arrangement of the several parts without departing from the spirit of this invention. It is also to be understood that this invention is well adapted for use in flying boats.

What is claimed as new is:

1. The combination of a boat body having a compartment therein, a flexible airtight and liquid proof sack therein, means whereby said sack may be inflated to cause the sack to substantially fill the compartment, the said sack being of the same shape as the interior of the compartment, and means encompassing the sack for holding the sack against full expansion under the pressure within the sack.
2. The combination of a boat body having a compartment therein, a flexible airtight and liquid proof sack in the compartment, a casing for the sack, said sack and casing conforming in shape to the interior of the compartment, and an inflation valve for the sack, said sack when inflated, substantially filling the compartment, said casing being of a size slightly less than the sack whereby the walls of the sack will be relieved of the air pressure therein by the casing exterior of the sack.
3. The combination of a boat body having a compartment therein, a plurality of sacks in the compartment, said sacks having substantially the same shape as the in-

terior of the compartment, a partition constructed of light material and disposed intermediate adjacent sacks and within the compartment, means whereby each of the sacks may be inflated to substantially fill the portion of the compartment occupied by the respective sacks, and means whereby the said partition will be relieved of the air pressure within the sacks.

4. The combination of a boat body having a compartment therein, a plurality of sacks in the compartment, said sacks having substantially the same shape as the interior of the compartment, a partition constructed of light material and disposed intermediate adjacent sacks and within the compartment, means whereby each of the sacks may be inflated to substantially fill the portion of the compartment occupied by the respective sacks, and a casing inclosing each of the sacks, said casing being of a size slightly less than the sacks whereby the walls of the sack and the partition will be relieved of the air pressure therein, by the casing exterior of the sacks.

In testimony whereof I have signed my name to this specification, in the presence of two subscribing witnesses, on this 26th day of January, A. D. 1917.

THOMAS P. BROOKE.
